ASH TRAY

Violet Clyde Ross and Joan Hall, also known as Joanetta Hall, Hawthorne, Calif.

Application March 2, 1953, Serial No. 23,840

Term of patent 3½ years

(Cl. D85—2)

We claim:

The ornamental design for an ash tray, as shown.
